MAGNETRON

Hans Erich Hollmann, Berlin, Germany, assignor
to Telefunkens Gesellschaft für Drahtlose Tele-
graphie m. b. H., Berlin, Germany, a corpora-
tion of Germany

Application January 14, 1939, Serial No. 250,877
In Germany January 26, 1938

3 Claims. (Cl. 250—27.5)

My invention relates to electron discharge devices of the so-called magnetron type in which the electrode system of the device is subjected to a magnetic field during the operation of the device.

Various magnetron tubes have of late been evolved and disclosed in which one or two cathodes are disposed outside the anode cylinder in order to protect the cathodes from the extra heating caused by electrons returning thereto. In one form of such tubes, the conventional form of magnetron has been preserved so far as the construction and arrangement of the anode is concerned; that is to say, the anode cylinder 10 may be closed upon itself or else be split into two, three or more segments which, individually or combined into groups, are associated with a suitable oscillatory circuit, for example, a Lecher-wire system. Another form of tube having external cathodes has a cylindrical anode (or anode cylinder) subdivided not into segments parallel to the axis, but by sections at right angles to the axis to result in two or more rings also united into groups. Inasmuch as in these two types of 20 tube, the electrons travel along spiral paths from the cathode into the interior of the anode cylinder, it is possible in one case by slit-fields parallel to the axis as well as in the other case by means of concentric fields to obtain delivery of 25 energy at the rhythm or rate of the rotation frequency or multiples thereof.

Fundamentally speaking, it would be self-suggesting to combine these two actions in a tube schematically illustrated in Figure 1 by subdividing the anode cylinder both into segments as well as into rings so that there results a magnetron tube comprising a great number of segments as indicated at S₁', S₁'' . . . S₂', S₂'', etc. However, it will be readily understood that the attempt to excite all of these different segments in phase or in phase opposition and to connect them together in a suitable way so as to result in two groups excited in phase must encounter serious difficulties, for the reason that the exciting frequencies to be considered for both modes of subdivision can be made equal only with great difficulties, and also on the ground that the complicated connection of such a great number of elementary segments, where ultra-high frequencies are concerned, could never be free from disturbing secondary actions, primarily because of the inductances of criss-crossing connecting wires.

The object of my invention is to provide an 55 electron discharge device of the magnetron type

of novel construction and having improved characteristics.

According to the invention, simultaneous subdivision or splitting in directions parallel to the axis and at right angles thereto is effected by dividing the anode cylinder into two or more helical segments by a helical split, the ensuing divisions or segments in the usual manner being connected with one another and with an oscillatory circuit. By such a step the electrons along 10 their spiral paths will repeatedly encounter split fields in the presence of a substantially perpendicular field and of the same rhythm, provided that the pitch of the helical splits is adapted to the operating conditions, in other words, to the 15 magnetic and the electrical field intensity.

A practical exemplified embodiment of a tube as here disclosed is illustrated in Figure 2 in schematic form, the tube being provided with two helical anode segments S₁ and S₂. The 20 cathode K is mounted at the left-hand end of the anode cylinder. This cathode is rearwardly shielded by means of a flat disc shield B. The open opposite end of the anode cylinder is closed by the disc electrode F, which, if desired, may be 25 impressed with a constant, positive auxiliary potential, and which is adapted to adjust the axial component of the motion of the electrons, that is, in the presence of a given magnetic field intensity, the pitch of the helical movement. The 30 anode cylinder, in a way as hereinbefore explained, is divided by means of two helical splits extending in a sense contrary to the rotational motion of the electrons, into two segments S₁ and S₂ both of which are connected with a suitable resonance circuit, say, an inductance clip or loop L. An electromagnetic coil M produces a magnetic field within the space surrounded by 35 said anode segments and parallel to the longitudinal axis of said segments. Inasmuch as the 40 time of rotation or circulation of electrons inside a homogeneous magnetic field, as well known, is always the same, it follows that the helical split field will always be traversed by electrons at the same rhythm; in other words, the segments at all points are excited at the same frequency. It will, of course, be understood that the helical splitting could be effected by three, 45 four, or more segments rather than in two; and just as in the conventional magnetron tube, the 50 connection thereof may be in pairs or in groups with segments placed parallel to the axis. In order that natural oscillations of the comparatively long helical segments may be prevented, it is preferable to connect the same at a number 55

of points by bridging clips. On the contrary, however, the segments could be used to act also as an oscillatable resonance system though in such case care must be taken so that standing waves will be set up along the segments. However, all of these steps are well known with the conventional magnetron tube, and they may similarly be adopted in connection with the tube here disclosed without the necessity of more detailed explanation.

It goes without saying that, as to the rest, all such ways and means as are conductive to improved conditions of excitation in connection with other types of tubes could be applied also to the tube here disclosed having helical splits. More particularly, the performance and efficiency of the tube is increaseable by providing two cathodes, one mounted at each end of the anode cylinder, without the basic idea of the invention, namely, to provide a helical split of the anode cylinder, experiencing any basic alteration. Moreover, as disclosed in connection with standard external cathode tubes, it is possible to mount in the axis of the discharge system a non-emissive cathode, say, in the form of a rod connected with the cathode proper, to the end of thereby insuring more symmetric voltage conditions.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the

purpose for which it is employed without departing from the scope of my invention as set forth in the appended claims.

What I claim as new is:

1. An electron discharge device having an envelope containing a cathode and an anode comprising a pair of segments provided with helical gaps between said segments, said anode segments being displaced longitudinally of said cathode, and means for producing a magnetic field within the space surrounded by said anode segments and parallel to the longitudinal axis of said anode. 5

2. An electron discharge device having an envelope containing a pair of anode segments having helical gaps therebetween, a cathode positioned at one end of said anode segments, an electrode positioned at the other end of said anode segments and adapted to have a positive potential applied thereto and means for producing a magnetic field within the space surrounded 10 by said anode segments and parallel to the longitudinal axis of said segments. 15

3. An electron discharge device having an envelope containing a pair of anode segments having helical gaps therebetween, a cathode positioned at one end of said anode segments, an electrode positioned at the other end of said anode segments and adapted to have a positive potential applied thereto and means for producing a magnetic field within the space surrounded by 20 said anode segments and parallel to the longitudinal axis of said segments, and a shielding device positioned on the other side of said cathode from said anode segments. 25
